SLIP

Glenn D. Johnson, Compton, Calif., assignor to
 Baash-Ross Tool Company, Los Angeles, Calif.,
 a corporation of California

Application April 8, 1940, Serial No. 328,517

11 Claims. (Cl. 24—263.5)

This invention relates to well drilling equipment and relates more particularly to slips for use in the rotary table of a well drilling rig. A general object of this invention is to provide practical, effective and improved rotary slips.

Another object of this invention is to provide slips embodying replaceable pipe engaging liners retained in the slip bodies by novel, dependable means.

Another object of this invention is to provide slips of the character mentioned in which the replaceable liners are removably secured in the slip bodies in such a manner that the vertical and rotational strains resulting from supporting the pipe and from breaking out the pipe joints, etc., are transmitted directly to the slip bodies.

Another object of this invention is to provide slips of the character mentioned in which the liner retaining means do not include pins, bolts, screws, or other parts liable to break, shear off, become loosened or detached.

Another object of this invention is to provide slips of the character mentioned in which the liner retaining means are simple and inexpensively embodied in the slip structure and provide for the quick easy removal and replacement of the liners.

A further object of this invention is to provide slips of the character mentioned in which the handles are hinged to the slip bodies so that they may always rest on the surface of the rotary table out of the path of the descending elevators when the slips are seated in the table and are arranged and formed for the most convenient and advantageous handling of the slips.

The various objects and features of my invention will be fully understood from the following detailed description of a typical preferred form and application of the invention, throughout which description reference is made to the accompanying drawings, in which:

Fig. 1 is a side elevation of a slip construction of the present invention arranged in the operative position in a rotary table bushing and engaging about a pipe, the bushing appearing in vertical section. Fig. 2 is a plan view of the parts illustrated in Fig. 1. Fig. 3 is an enlarged face elevation of one of the slips being a view taken substantially as indicated by line 3—3 on Fig. 2, with a portion broken away to illustrate the details of a hinge connection. Fig. 4 is an enlarged fragmentary vertical detailed sectional view taken as indicated by line 4—4 on Fig. 3. Fig. 5 is a horizontal detailed sectional view taken as indicated by line 5—5 on Fig. 4 and Fig. 6 is an en-

larged fragmentary detailed sectional view illustrating the active surface of one of the liners.

The features of the invention are adapted to be embodied in slip structures varying somewhat in character. In the following detailed disclosure I will describe a typical preferred form and application of the invention, it being understood that the invention is not to be construed as limited or restricted to the particular details set forth.

The slip structure of the present invention may be said to comprise, generally, hinged connected bodies 10, liners 11 for engaging the work or pipe P, means 12 for removably retaining the liners 11 on the bodies 10, and handles 13 and 14 for the slip structure.

In the slip structure illustrated there are three connected or hinged slip bodies 10, it being understood that the invention is not restricted to this type of construction and is capable of embodiment in slips or slip sets having two, three, or more individual or connected slip bodies. The bodies 10 are tapered or wedge shaped parts adapted to be inserted in the tapered opening O of a rotary table bushing B to engage about and grip or support the pipe P. The slip bodies 10 are alike or complementary and have substantially vertical inner sides and sloping tapered outer sides for engaging in the opening O. The main outer surfaces 15 of the bodies 10 are transversely or horizontally convex and are downwardly and inwardly tapered to conform to the wall of the tapered bushing opening O. The opposite edges or sides 16 of the bodies 10 are bevelled away or are rearwardly convergent. The upper outer corners of the bodies 10 are bevelled away or sloped downwardly and outwardly and the outer lower corners of the bodies may be bevelled, as desired. The bevelled tops of the bodies 10 are preferably cored out or ribbed to reduce the material and weight. The lower ends of the bodies 10 preferably have flat horizontal surfaces 17 adapted to rest on the rotary table or other support so that the slips may stand upright when not in use. The inner sides of the slip bodies 10 are of special formation to receive the liners 11 and the retaining means 12.

Hinges connect the slip bodies 10 so that the tool is unitary or capable of insertion, removal and handling as a unit. The hinge means for connecting the three slip bodies 10 may comprise, vertically spaced lugs 18 projecting from the opposite sides 16 of the intermediate body 10 and complementary lugs 19 projecting from the op-

posing sides of the other bodies 10. The lugs 19 are disposed above and below the lugs 18 of the intermediate body 10 and have vertical openings 20. Vertical openings 21 of larger diameter pass through the lugs 18. Hinge pins 22 are arranged through the openings 20 and 21 to hingedly connect the bodies 10. The pins 22 pass through the openings 21 with substantial clearance and are rather closely received in the openings 20. The opposing ends of the openings 21 have bevelled or tapered sockets and shiftable sleeves 23 are arranged on the pins 22 and have tapered ends cooperating with the tapered sockets of the openings 21. Springs 24 surround the pins 22 and are arranged under compression between the sleeves 23 to urge the tapered parts of the sleeve in the tapered parts of the openings 21. The spring urged sleeves 23 yieldingly hold the bodies 10 against relative tilting or rocking. Tubes 25 surround or enclose the springs 24 and portions of the sleeves 23. The spring hinges just described dependably connect the three bodies 10 yet allow a limited relative movement of the bodies 10 so that they may evenly conform to and fit in the bushing opening O.

The liners 11 are the wear taking, object or pipe engaging elements of the slips and in accordance with the invention are removable and replaceable. In the preferred construction there are two similar or identical liners 11 carried by each slip body 10. The liners 11 are elongate members provided with cylindrically convex outer surfaces 26 and cylindrically concave inner sides. The inner sides of the liners 11 are finished to dependably grip the object or pipe P. In the case illustrated the inner sides of the liners 11 have pluralities of horizontally extending vertically spaced raised sections 27 each presenting a roughened surface. As best illustrated in Fig. 6 of the drawings the surfaces of the sections 27 present multiplicities of truncated pyramids 28. The flattened or truncated pyramids 28 are effective in preventing slipping of the object or pipe P and penetrate the surface portions of the pipe P to minimum extent. The upper and lower ends of the liners 11 are flat and horizontal while the sides or edge surfaces 29 of the liners are flat and vertical. The edge surfaces 29 are of substantial width and in accordance with the invention are inwardly convergent, that is, the surfaces 29 of a liner 11 converge toward the axis of curvature of the inner and outer surfaces of the liner.

The means 12 for retaining the liners 11 on the slip bodies 10 are important features of the invention. The means 12 include shoulders and surfaces on the inner sides of the bodies 10 for supporting and cooperating with the liners. Each slip body 10 is provided at its inner side with an upwardly facing lower shoulder 30 and a downwardly facing upper shoulder 31. The shoulders 30 are adjacent the lower ends of the bodies 10 and the shoulders 31 are in spaced adjacent relation to the upper ends of the bodies. As illustrated, the shoulders 30 and 31 are substantially horizontal and parallel. The inner side of each slip body 10 is provided with a pair of spaced opposing vertical abutments or surfaces 32. The surfaces 32 occur adjacent the inner corners of the bodies 10 and lie in vertical planes. In accordance with the invention the abutments or surfaces 32 are inwardly convergent, converging toward the axes of curvature of the convex inner sides of the bodies 10.

A pair of liners 11 is arranged against the

inner side of each body 10 and the outer edge surfaces 29 of the liners are adapted to bear against or engage the abutments or surfaces 32. The pitch or convergence of the surfaces 32 is such that the edge surfaces 29 of the liners 11 evenly bear on the surfaces 32 when the outer convex surfaces 26 of the liners conform to and bear on the inner sides of the bodies 10. The parts are related and proportioned so that the inner edge surfaces 29 of the liners 11 are spaced apart when the outer edge surfaces 29 bear against the surfaces 32 as just described. The upper and lower ends of the elongate liners 11 are adapted to engage the shoulders 30 and 31 for the direct transmission of vertical forces from the liners 11 to the slip bodies 10.

The means 12 further include central or intermediate grooves 35 in the inner sides of the slip bodies 10 and keys 36 fitting the grooves. 20 The grooves 35 are preferably polygonal or rectangular having flat vertical walls and extend from the lower shoulders 30 upwardly to the upper ends of the slip bodies 10. As best illustrated in Fig. 5 of the drawings the grooves 35 are considerably wider than the spaces 37 between the adjacent edge surfaces 29 of the liners 11. The keys 36 are arranged in the grooves 35 to engage between the opposing edge surfaces 29 of the pairs of liners 11 to hold the liners 30 against horizontal displacement and movement. The keys 36 are elongate members and are substantially T-shaped in horizontal cross section having main portions that occupy the grooves 35 and having reduced portions that project from 35 the grooves 35 to fit between the adjacent surfaces 29 of the liners 11. The keys 36 are entered in the upper ends of the grooves 35 and are passed downwardly until their lower ends rest on the shoulders 30. With the lower ends 40 of the keys 36 bearing on the shoulders 30 the keys project upwardly beyond the shoulders 31.

Means are provided for holding the keys 36 against upward movement. Radial openings 39 are provided in the bodies 10 and extend rearwardly from the grooves 35 to the rear sides of the bodies. Cotter keys 40 are passed outwardly or rearwardly through the openings 39 and their tails are spread and turned back against the rear sides of the bodies 10. The heads of the cotter keys 40 project into the grooves 35 at the upper ends of the keys 36 to prevent upward movement of the keys. From an inspection of Fig. 5 it will be apparent that the keys 36 engaged between the opposing surfaces 29 of the adjacent liners 11 hold the liners in positions where their outer edge surfaces 29 bear on the body abutments or surfaces 32. Thus the keys 36 have a "keystone" action and definitely key or lock the slips 11 against movement and displacement.

The handles 13 and 14 are provided to facilitate the ready manual manipulation of the slips. The handle 13 may be termed the rear handle and is connected with the intermediate body 10 while the handles 14 are connected with the "end" bodies 10. A pair of spaced lugs 41 is provided on the rear side of the intermediate body 10 above its main outer surface 15 and a pin 42 is arranged in horizontal openings in the lugs 41. The handle 13 is pivotally supported by the pin 42. The handle 13 is curved or bent having an inner part 43 and an upper outwardly projecting part 44. A loop-like or stirrup-shaped grip 53 is provided on the outer end of the handle part 44. The grip 53 is provided with

depending skirts 54 adapted to rest on the surface of the table to hold the body of the grip elevated for easy engagement. The handles 14 are similar in shape to the handle 13 having inner parts 43^a and outer parts 44^a. The inner parts 43^a of the handles 14 are received between the pairs of lugs 45 on the upper rear portions of the end-most bodies 10. Pivot pins 46 are arranged in transverse openings in the lugs 45 to pivotally support the handles 14. The outer ends of the handle portions 44^a have loop-like grips 47. The grips 47 are adapted to rest on the upper surface of the rotary table when the slips are engaged in the opening O. The part 43 of the handle 13 is engageable with a substantially vertical rear surface 50 of its body 10 to limit the upward swinging of the handle. The broken lines in Fig. 1 of the drawings illustrate the raised or uppermost position of the handle 13. The portions 43^a of the handles 14 are engageable with rear surfaces of their respective bodies to limit the upward pivoting of the handles 14. The handles 13 and 14 are provided with stop means for limiting their downward pivoting. Stops 51 are formed on the lower ends of the handles 13 and 14 and are adapted to engage the bodies 10 to limit the downward pivoting of the handles. The handles 13 and 14 mounted and shaped as above described automatically assume the lowered positions upon being released and when in these positions are out of the paths of the descending elevators and yet are conveniently accessible for manual engagement.

It is believed that the utility and practicability of the improved slip construction of the present invention will be readily understood from the foregoing detailed description. When the slips are in operation the liners 11 engage the object or pipe P to support the same or to transmit rotation thereto. The truncated pyramids 28 of the liners 11 dependably resist or prevent slippage between the pipe P and the slips. The keys 36 engaged between the opposing surfaces 29 of the adjacent liners 11 positively key or lock the liners in positions where they bear on the surfaces 32 and the inner sides of the bodies 10. The liners 11 directly engage the body shoulders 30 and 31 and the body surfaces 32 for the direct transmission of both vertical forces and rotational forces to the body and the retaining means or lock means are subjected to little or no strain. If it becomes desirable or necessary to replace the liners 11 the cotter keys 40 are driven from the openings 39 and the keys 36 are slid from the grooves 35. Upon removal of the keys 36 the liners 11 may be easily detached from the bodies 10. New or replacement liners 11 may be readily positioned on the bodies 10 and the keys 36 may be replaced and locked in position by the cotter pins 40 to secure the new or replacement liners.

Having described only a typical preferred form and application of my invention, I do not wish to be limited or restricted to the specific details herein set forth, but wish to reserve to myself any variations or modifications that may appear to those skilled in the art, or fall within the scope of the following claims:

Having described my invention, I claim:

1. In a slip of the character described, a slip body having spaced longitudinal abutments on its inner side lying in inwardly converging planes, a pair of removable liners arranged against the inner side of the body to be in spaced

relation, the outer longitudinal edges of the liners being inwardly convergent to fit against the abutments, and a longitudinal key inserted between the liners holding the liners against the abutments to be locked against inward movement thereby.

2. In a slip of the character described, a slip body having spaced opposing abutments on its inner side lying in inwardly converging planes, 10 a pair of removable liners at the inner side of the body having inwardly convergent inner and outer edges, the liners being arranged to have their outer edges in spaced substantially parallel relation, and a removable key engaged between the inner edges of the liners to maintain the engagement of said outer edges with the abutments.

3. In a slip of the character described a slip body, a shoulder on the inner side of the body, spaced opposing locking abutments on the inner side of the body extending transversely of the shoulder and lying in inwardly convergent planes, 25 a pair of liners at the inner side of the body having ends engaging the shoulder, the liners being arranged in side by side relation with their inner edges in spaced relation and their outer edges in said convergent planes to have locking engagement with said abutments, and removable key means on the body engaged between said inner edges of the liners to maintain said locking engagement so that the liners are locked against inward displacement, said abutments and key means transmitting forces transverse of the shoulder from the liners to the body.

4. In a slip of the character described, a body, spaced opposing generally parallel shoulders on the inner side of the body, spaced opposing abutments on the inner side of the body extending transversely of the shoulders and lying in inwardly converging planes, two liners bearing against and substantially conforming to the inner side of the body with their ends against said shoulders to be held against movement in one direction by the shoulders, the liners having inwardly convergent inner and outer edge surfaces, the liners being arranged to have their outer edge surfaces in said converging planes to be in locking engagement with said opposing abutments of the body and to have their inner edge surfaces in spaced relation, and a key removably carried by the body and engaging between said spaced inner edge surfaces of the liners to maintain said locking engagement, the liners being held against movement in a direction transverse of the first named direction and against inward displacement by said locking engagement with said opposing abutments of the body.

5. In a slip of the character described, a body having a substantially horizontal shoulder and having spaced opposing substantially vertical lock abutments on its inner side, a pair of liners arranged to bear against the inner side of the body and to have end faces bear on the shoulder, the liners having substantially vertical outer edge lock surfaces formed to lock with said abutments when shifted horizontally into cooperation with the abutments, the liners being arranged with their said edge lock surfaces in cooperation with the lock abutments of the body and with their inner vertical edge surfaces in spaced relation, and a removable key 65 on the body engaging between the spaced inner

edge surfaces of the liners to maintain the locking engagement between the lock abutments and said edge lock surfaces.

6. In a slip of the character described, a body having a recess in its inner side, the side walls of the recess lying in inwardly convergent planes, a pair of liners seated in the recess with their upper and lower ends bearing on the end walls of the recess, the side edges of the liners being inwardly convergent to lie in said planes in cooperation with said side walls, and a removable key engaging between the inner side edges of the liners to hold the outer side edges of the liners in cooperation with the side walls of the recess so that the liners are retained in the recess by said cooperation.

7. In a slip of the character described, a body having a substantially horizontal shoulder and a substantially vertical undercut abutment on its inner side, a liner removably arranged to bear against the inner side of the body and to have an end bear on the shoulder and a vertical edge in conforming engagement with said vertical surface, and a key engaging the opposite vertical edge of the liner to maintain said engagement between the abutment and the first named vertical edge and thus hold the liner in place.

8. In a slip of the character described, a body having a concave inner side, a substantially horizontal shoulder on said inner side and a substantially vertical shoulder on said inner side lying in a plane substantially radial relative to the axis of curvature of said inner side, a removable liner arranged against and generally conforming to the inner side of the body with an end bearing on the horizontal shoulder, the liner having one vertical edge lying in said radial plane to have locking engagement with the vertical shoulder, and a vertical key engaged against the opposite edge of the liner to retain the liner against said vertical shoulder to be retained thereby.

9. In a slip of the character described, a body having a recess in its inner side, the side walls of the recess lying in inwardly convergent planes, 45

there being a vertical groove in the back wall of the recess, a pair of liners seated in the recess with their upper and lower ends engaging the end walls of the recess, the vertical edges 5 of the liners being inwardly convergent and the outer vertical edges of the liners lying in said planes to lock with the side walls of the recess, and a key removably arranged in the groove and having a part engaged between the inner edges 10 of the liners to maintain said outer edges in locking engagement with said side walls whereby the liners are locked against displacement.

10. In a slip of the character described, a body having a recess in its inner side, the side walls of the recess lying in inwardly convergent planes, there being a vertical groove in the back wall of the recess, a pair of liners seated in the recess with their upper and lower ends engaging the end walls of the recess, the vertical edges 15 of the liners being inwardly convergent and the outer vertical edges of the liners lying in said planes to have locking cooperation with the side walls of the recess, a key inserted in the groove to engage between the inner edges of the liners 20 to maintain said outer edges in locking engagement with said side walls and thus lock the liners against displacement, and means retaining the key in the groove.

11. In a slip of the character described, a body having a recess in its inner side, the side walls of the recess lying in inwardly convergent planes, there being a vertical groove in the back wall of the recess, a pair of liners seated in the recess with their upper and lower ends engaging the end walls of the recess, the vertical edges 30 of the liners being inwardly convergent and the outer vertical edges of the liners lying in said planes to have locking cooperation with the side walls of the recess, the liners partially overlying the groove, a key inserted in the groove, and a rib on the key fitting between the inner edges of the liners to maintain said outer edges in locking engagement with said side walls 35 and thus lock the liners against displacement.

GLENN D. JOHNSON.
